FRANK E. KINSMAN, OF PLAINFIELD, NEW JERSEY.

ICE-CLEARING AND CONTACT WHEEL FOR ELECTRIC RAILWAYS.

No. 917,735.

Specification of Letters Patent.

Patented April 6, 1909.

Application filed March 1, 1905. Serial No. 247,980.

To all whom it may concern:

Be it known that I, FRANK E. KINSMAN, a citizen of the United States of America, residing in the city of Plainfield, in the county 5 of Union, State of New Jersey, have invented an Improved Ice-Clearing and Contact Wheel for Electric Railways, of which the following is a specification.

One of the main objects of my invention is 10 to provide an electric railway system with an efficient means for clearing the third or contact rail of ice and sleet in winter. I prefer to so construct such means that they may serve also as an electric contact device to 15 supply current to the motors and other translating devices on the cars from the rail. This object I attain by providing the car with a wheel having a bearing face to bear upon the third rail. With this, I prefer to 20 combine means to retard or otherwise modify the natural rotation of the wheel caused by contact of the latter with the rail, so as to secure a scraping contact, either for ice-clearing or contact purposes, or both.

25 In the accompanying drawings Figure 1 is a side elevation of part of a car provided with my improvement; Fig. 2 is a cross-section; Fig. 3 is a cross-section to a larger scale through the contact wheel; Fig. 4 is a side elevation of the same; Fig. 5 is an edge view of a modified form of cutting wheel; and Fig. 6 is a side view of another modified form of wheel.

Referring to Figs. 1 and 2, A indicates the 35 body of the car and B indicates the third rail, by which current is to be supplied to the motors and other translating devices on the cars.

I suitably mount upon a bracket, such as 40 D on the car (Figs. 1 and 2), a wheel C in such a position that it may travel in contact with and thereby rotate on the surface of the third rail B. The periphery or bearing surface of this wheel is preferably convex or 45 rounded in cross-section, as indicated in Figs. 2 and 3, so that as the crown of the face bears upon the rail with a suitable pressure, ice or sleet which has formed upon the surface of the rail will be cut by a crushing, cracking, or 50 splitting action, and be thereby broken off. To make this action more effective, however, I provide means whereby the rotation of the wheel may be retarded, or, if found desirable, may be wholly prevented. For this purpose, 55 I prefer to provide a brake shoe S with fluid pressure, electromagnetic or other means un-

der the control of the engineer to cause the shoe to bear upon the wheel (axle, side face, or periphery) with any desired pressure. By preference I mount the brake shoe to bear 60 upon the periphery of the wheel diametrically opposite the point at which the wheel bears upon the rail, as shown. In the present instance, I have shown the shoe as acted upon by the piston rod p of a piston in a 65 cylinder P carried by the car, there being a system of pipes P¹ leading to a valve E under the control of the engineer, who can supply air or other suitable fluid pressure to act upon the piston in the cylinder P and so apply the brake shoe S to the wheel C. When 70 the brake shoe is thus applied to the wheel so as to retard the rotation of the wheel, caused by the contact of the wheel with the rail, the effect will be not only to cut and break the 75 ice or sleet on the rail, but also surely to brush it off. A spring, as indicated at S by dotted lines in Fig. 3, may be used to free the brake from the wheel when released from the air or other pressure, as by the proper 80 manipulation of the valve E.

The rim r of the wheel C may be suitably insulated from the body r¹, as indicated for example by heavy lines in Fig. 3, and there may be a collector ring r² on the car axle connected by insulated conductor with the rim of the wheel. The brake shoe S and cylinder P may be insulated from other metal parts of the car in any suitable way, and the air piping 85 may be insulated by using a rubber hose connection therein at a suitable point.

Although I have spoken of the wheel C as having a bearing face of convex cross-section, I do not intend by that expression to limit myself to a strictly rounded convexity, for I 95 may use a wheel with a relatively sharp bearing face, instead of a rounded cutting edge, as indicated in the edge view (Fig. 5), but such a wheel has a substantially convex cross-section. I prefer the form shown in Figs. 2 and 100 3, however, as that is better adapted for use in conjunction with the retarding means to force the ice and sleet off the rail, and also because such a wheel is better adapted to be used as a collector wheel to carry current to 105 the motors and other devices on the cars, if it be desired to use it in that way. It is also an advantage to employ the retarding means in connection with the wheel, when used for contact purposes, for by that means a scraping contact of moderate but sufficient effect 110 can be secured. If the wheel is to be used

for ice-cutting purposes only, it may be further modified by constructing its periphery with corrugations or teeth x , as shown in Fig. 6. In this modification the brake shoe may be applied to the side face or faces of the wheel, as indicated by dotted lines S^1 .

I claim as my invention—

1. An electric railway car, provided with an electric contact ice-cutting wheel adapted to bear upon the third rail having its bearing surface formed to cut the ice on the rail and electric connections therefor, said wheel constituting the sole electric contact member for said third rail.
15. 2. An electric railway car, provided with an ice-cutting and contact wheel having a bearing face of rounded convex cross-section and adapted to bear upon the third rail.
20. 3. An electric railway car, provided with an ice-cutting wheel adapted to bear upon the third rail in combination with means to retard the rotation of the wheel, the rim of the wheel being insulated from the car, and with electrical connections.
25. 4. An electrical railway car, provided with an ice-cutting wheel having a bearing face of rounded convex cross-section, and adapted to bear upon the third rail in combination with means to retard the rotation of the wheel.
30. 5. An electric railway car, provided with an ice-crushing and contact wheel having a bearing face of rounded convex cross-section and adapted to bear upon the third rail.
35. 6. An electric railway car, provided with an ice-cutting wheel adapted to bear upon the third rail and having a bearing face of rounded convex cross-section in combina-

tion with a brake adapted to bear upon the wheel, and means to apply and release the 40 brake.

7. An electric railway car, provided with an ice-cutting wheel adapted to bear upon the third rail in combination with a brake adapted to bear upon the wheel, and fluid 45 pressure means to apply the brake.

8. An electric railway car, provided with an ice-cutting wheel adapted to bear upon the third rail in combination with a brake adapted to bear upon said wheel, and means 50 under the control of the engineer to apply the brakes.

9. An electric car, provided with an ice-crushing and contact wheel adapted to bear on the third rail in combination with a brake 55 shoe, and means for applying the shoe to the wheel at a point diametrically opposite that at which the wheel bears on the rail and electrical connections to the wheel.

10. An electric car, provided with a contact and ice-crushing wheel adapted to bear on the third rail in combination with means 60 to modify the natural rotation of the wheel and electrical connections therefor.

11. An electric car, provided with a contact and ice-crushing wheel adapted to bear on the third rail in combination with means 65 to retard the rotation of the wheel and electrical connections therefor.

In testimony whereof I have signed my 70 name to this specification in the presence of two subscribing witnesses.

FRANK E. KINSMAN.
